UNITED STATES PATENT OFFICE.

HERMANN M. KESSELRING, OF CHICAGO, ILLINOIS.

X-RAY TUBE.

1,092,489.

Specification of Letters Patent.

Patented Apr. 7, 1914.

Application filed October 17, 1912. Serial No. 726,230.

To all whom it may concern:

Be it known that I, HERMANN M. KESSELRING, a subject of the Emperor of Germany, residing at Chicago, in the county of Cook 5 and State of Illinois, have invented a new and useful Improvement in X-Ray Tubes, of which the following is a specification.

In the use of X-ray tubes, as hitherto constructed, they frequently puncture at points 10 adjacent to the electrodes, and more especially at or near the junction of the body and handle portions at the cathode side of the tube. The primary cause of this puncturing is that the surface portions of the 15 metal electrode become oxidized and metal oxid particles are deposited upon the surface of the glass. When a particle of metal oxid lodges upon the glass at a point near the cathode, more especially, the current is 20 apt to jump from the cathode to such particle causing a spark which punctures the glass at that point and destroys the usefulness of the tube.

My object is so to improve the construction of X-ray tubes as to obviate or, at least, 25 greatly diminish the said danger.

It is further my object to provide means for the rapid withdrawal of heat from the body of the tube, to prevent overheating 30 thereof and thus render it easier to handle with less liability of injury to the tube.

The accompanying drawing is a sectional view of an X-ray tube, of known construction, provided with my improvements.

35 The tube is of glass having the usual spherical body-portion 1, and the hollow extensions 2, 3 forming handles. In the extension 2 is a cathode 4 formed with a head, having a concave face 5, and a stem 6.

40 The numeral 7 designates the target which serves likewise as the main anode of the tube. The stem 8 of the anode is in the extension 3. On the body-portion is the usual regulator 9 and also a hollow extension 10, 45 containing an assistant anode 11.

Supported in the part 2 is an insulating shield 12, preferably of lead-glass. The shield 12 surrounds the stem and head of the cathode leaving only the concave face 5 thereof exposed. The shield 12 is out of contact with the stem 6 of the cathode except at the point 13 where it is contracted about the same to steady it. The shield 12, being of lead-glass, by which I mean glass 55 having a material percentage of lead in its composition, is impervious to cathode rays

and operates as a current insulator serving to confine the discharge of current to the concave face 5, and squarely against the target 7, thereby limiting dissemination of 60 the cathode rays in the tube. The shield 12 also serves as a heat-insulator for the cathode which protects the extension 2 and adjacent body-portion 1 from the heat generated at the cathode.

65 The anode or target 7 is a solid cylindrical metal block with an inclined face containing a platinum disk 14. Surrounding the target is a metal sleeve 15 having an opening 16 through which the X-rays are projected.

70 Within and integral with the extension 3 is a preferably lead-glass shield formed with an inner-tubular portion 17 loosely surrounding the stem 8 and attached by the 75 metal sleeve or ferrule 18 to the cylindrical head 7. Integral with the inner sleeve 17 is an outer lead-glass sleeve or tube 19 surrounding the parts 17, 18 and 15, and extending slightly beyond the latter. It has 80 an opening 20 registering with the opening 16. The inner and outer sleeves or tubes 17, 19, serve as current and heat-insulators for the head and stem of the anode and protect the surrounding extension 3 and adjacent 85 body-portion 1 from the heat of the anode. The outer-end portion of the extension 3 is enlarged into a bulb 22, and is of 90 thinner glass than the body-portion of the tube. The glass being thinner permits heat to discharge or radiate therefrom more rapidly, and in practice much of the heat generated at the anode is conducted, along the parts 7, 8, 18, 17 and 19 to the thin glass bulb 22 whence it radiates rapidly into the 95 surrounding atmosphere. The bulb 22, in practice, serves in fact to withdraw much of the heat from the main bulb, or body-portion, 1 and thus diminish danger of injury to the tube in the handling thereof.

100 The assistant anode 11 is loosely surrounded, in the part or extension 10 of the tube by a, preferably lead-glass, tube, or shield, 21, integral with the part 10 and serving as a current and heat-insulator.

105 While the tube is in operation the cathode 4, more especially, becomes heated to a high temperature and the main purpose of the shield 12 is to reduce the heat radiated therefrom to the extension 2 and adjacent body-portion 1 of the tube. It has been found in practice that if the latter become heated to 110

a high temperature they are very apt to fracture if touched with metal or any comparatively cold object. Furthermore, heating, particularly, of the extension 2, interferes with the handling of the tube by the operator. The shield 12 absorbs much of the heat radiated from the cathode and thus serves to prevent the surrounding tube from being heated to a degree which will cause it to fracture and puncture, if touched with metal, as by a ring on the operator's finger, and also prevents the extension 2 from being heated to a temperature which will interfere with ready handling thereof by the operator. The inner and outer tubes or shields 17, 19 serve to insulate the target or anode and to protect the surrounding parts 3 and 1 of the tube from the heat thereof. The shields 17, 19, furthermore, serve to prevent metal oxid loosened from the anode from being deposited against adjacent parts of the handle 3 and body-portion 1, where the current might spark across and puncture the glass.

In the use of my improved tube, any metal oxid particles discharged from the cathode will deposit in and tend to remain in the shield 12, being kept thereby against depositing on the inner surface of the handle 2 and the adjacent part of the body-portion 1. One of the most serious troubles encountered in the use of X-ray tubes, as hitherto provided, is that of their puncturing due, as before stated, to deposits of metal oxid on the inner surface of the handle or body-portion near enough to the cathode for the current to spark across. This sparking against the glass of the handle or body-portion is apt to, and frequently does, result in puncturing

the glass thereby destroying the usefulness of the tube. When the particles of metal oxid remain in the shield 12, the current may jump thereto and cause sparks, but as the shield is very hot and not exposed to the chilling effect of the outside atmosphere, it is not liable to puncture, though if it did puncture, it would not destroy the usefulness of the tube. Incidentally the lead glass shields described reduce danger of X-ray burns in the handling of the implement.

The foregoing description is intended to convey a clear understanding of my improvements in what I now believe to be the best form of their embodiment, and no undue limitation should be understood therefrom. It is my intention to claim all that is novel in my invention, and that the claims shall be construed as broadly as the prior state of the art may warrant.

What I claim as new and desire to secure by Letters Patent is:—

1. In an X-ray tube, the combination with the glass body-portion and electrodes, of a glass extension containing one of the electrodes and formed along its outer-end portion with a compartment of thinner glass than the said body-portion, for the purpose set forth.
2. In an X-ray tube, the combination with the glass body-portion and electrodes, of a glass extension having an enlarged outer-end portion forming a compartment of thinner glass than the said body-portion, for the purpose set forth.

HERMANN M. KESSELRING.
